UNITED STATES PATENT OFFICE.

SAMUEL HUFFMAN, OF MATANZAS, KANSAS, ASSIGNOR OF ONE-HALF TO
NUMON N. HORTON, OF KANSAS CITY, MISSOURI.

SEED-DRILL.

SPECIFICATION forming part of Letters Patent No. 243,908, dated July 5, 1881.

Application filed October 28, 1880. (No model.)

To all whom it may concern:

Be it known that I, SAMUEL HUFFMAN, a citizen of the United States, residing at Matanzas, in the county of Chautauqua and State 5 of Kansas, have invented a new and useful Improvement in Seed-Drills, of which the following is a specification.

My invention relates to improvements in spreading seeds by the foot of a drill in a more broadcast manner than is done by drills in general use or heretofore used. I accomplish this by placing a spreading-cone in the lower end of a boot, which is in connection with a foot provided with partitions and grooves, for 15 spreading the seeds under the soil.

The accompanying drawings fully represent my invention, in which Figure 1 is a perspective view of the tube and shoe. Fig. 2 is a vertical section of the same; and Fig. 3 is a 20 top view of the shoe, showing the spreaders in the foot, the partitions, chambers, and spreading or scattering cone.

In the drawings and specification similar letters refer to similar parts.

25 In constructing my invention I secure to the boot A a foot, B C c c', firmly attached to the bottom thereof. The shovel B, for cutting and opening the earth in front of the boot A, is solid, as shown in Figs. 1 and 2. From the 30 front part of the boot to the rear of the foot I form a chamber by and between two plates. This chamber is in connection with the chamber in the boot, forming a continuous passage for the seeds until they are deposited in the soil.

35 The chamber formed between the plates C c', Fig. 2, is divided into smaller chambers by the partitions D D. (Shown in Figs. 2 and 3.) These partitions D D diverge from a point under the cone E. The cone E is situated in the lower part of the boot and rests on the partitions or flanges D D D, as shown in Figs. 2 and 40 3. The cone E is attached to the boot A by a screw or any suitable means. A portion of the cone should be removed at its base to give 45 a proper bearing against the inside surface of the boot, also to remove the point of the cone from the center of the boot for the purpose of distributing the seeds more equally into the different chambers. The cone E may be grooved or smooth. The seeds falling from the seed-

box upon the cone E are, by its shape and situation, distributed to the chambers more evenly than could otherwise be done without it, or if of a different form. The seeds falling from the 55 distribution box or hopper pass through the boot A, strike the cone E, and are thrown or deflected into the chambers, through which they pass by the inclination of the chambers and the force of gravity, and are deposited into 60 the earth in a broadcast form.

The chambers formed by the partitions D D 65 are subdivided by forming slightly-raised divisions, or by grooves between the partitions D D.

In Fig. 3 the boot A and a part of the upper 70 surface of the plate B C are broken away to show the construction of cone E, also the partitions D D, the chambers, and the subdivisions d.

The plate C at c, Figs. 2 and 3, is shown to project over enough to protect the outlet of the chambers from being clogged by the falling dirt.

The ears or lugs a a' are for attachments for 75 drawing and lifting the boot in the ordinary way.

The partitions D D D, Figs. 2 and 3, form separate chambers, and the chambers are particularly necessary on sidling ground. They insure a broadcast that would not be effected by corrugations. The entire passage of the seeds being secure from interfering substances from the outside insures their being deposited in a broadcast form.

85 What I claim, and desire to secure by Letters Patent, is—

1. In a drill or broadcasting-tube, the deflector E and partitions D, substantially as described and shown.
2. In a drill or broadcasting-tube, the cone-shaped deflector E, partitions D D, and grooves d d, substantially as described and shown.
3. In a drill or broadcasting device, the tube A, foot B, rear extension, C c', partitions D D, 95 and grooves d d, substantially as described and shown.

SAMUEL HUFFMAN.
